UNITED STATES PATENT OFFICE.

JOHN E. MATTHEWS, OF ASHLAND, OHIO.

TRANSFER MEANS FOR DOORS.

1,098,516.

Specification of Letters Patent.

Patented June 2, 1914.

Application filed January 21, 1914. Serial No. 813,460.

To all whom it may concern:

Be it known that I, JOHN E. MATTHEWS, a citizen of the United States, residing at Ashland, in the county of Ashland and State of Ohio, have invented certain new and useful Improvements in Transfer Means for Doors, of which the following is a specification.

My invention relates to means for supporting and handling bodily movable or slideable doors, whereby they may be conveniently transferred to a point remote from their normal operative position, as for example, from the forward end or side of a room, which they normally close, to the rear end or side thereof, to occupy an out-of-the-way position.

An important object of the invention is to provide means of the above mentioned character, which are simple in construction, inexpensive to manufacture, easy to operate, strong, and durable.

A further object of the invention is to provide means of the above mentioned character, which may be installed in the average building, without materially altering the construction thereof.

A further object of the invention is to provide means of the above mentioned character, whereby comparatively heavy doors may be moved a substantial distance, as from one end of a room to the other, in a convenient and expeditious manner, without undue effort on the part of the operator.

Other objects and advantages of this invention will be apparent during the course of the following description.

In the accompanying drawings forming a part of this specification and in which like numerals are employed to designate like parts throughout the same, Figure 1 is a perspective view of apparatus embodying my invention, Fig. 2 is a plan view of the same, parts being broken away for the purpose of illustration, Fig. 3 is a vertical sectional view taken on line 3—3 of Fig. 2, Fig. 4 is a transverse sectional view taken on line 4—4 of Fig. 2, and, Fig. 5 is a detail horizontal sectional view through the transfer track-rail section and one of the relatively sta-

tionary track-rails. Fig. 6 is a section on the 50 line 6—6 of Fig. 2.

In the drawings, wherein for the purpose of illustration is shown a preferred embodiment of my invention, the numeral 10 designates an upper beam, preferably extending transversely of or between two rooms, which are adapted to be thrown into free and unobstructed communication with each other, by the manipulation of doors, to be described. The beam 10 is preferably disposed adjacent the ceiling and is preferably supported between its ends, by means of a centrally arranged vertical post 11, attached thereto by means of spikes or nails 12, as shown. This post is not essential and may be dispensed with, if desired.

The numeral 13 designates a longitudinally extending beam, arranged preferably adjacent the ceiling and connected at one end with the transverse beam 10, through the medium of the nails or spikes 12 or the like. In the present illustration it is considered that the beam 13 extends longitudinally of the rear room from the forward to the rear ends thereof.

Attached to the transverse beam 10 upon opposite sides of and spaced from the post 11 are suspension track-rails 14 and 15, depending therefrom, and preferably formed approximately L-shaped in cross-section. The track-rails 14 and 15 are arranged upon opposite sides of the beam 10 and are oppositely faced.

The numeral 16 designates a track-rail, preferably identical with the track-rails 14 and 15, and attached to and depending from the longitudinally extending beam 13, as shown. The track-rail 16 is spaced from the inner ends of the track-rails 14 and 15, and is preferably arranged at substantially a right angle thereto. It is obvious that the beams 10 and 13 may be dispensed with, if desired, in which event the track-rails will be secured to the ceiling or otherwise supported, by any suitable means.

The numeral 17 designates a swinging transfer track-rail section, which is preferably approximately L-shaped in cross-section

to correspond generally to the shape of the track-rails. At its inner end the transfer track-rail section 17 is provided with a laterally extending apertured ear 18, pivoted to 5 a shoulder 19 of the post 11 by means of a bolt 20 or the like. At its free end this transfer track-rail section has slidable engagement with and is supported by a curved or semi-circular horizontally arranged track- 10 support 21, which is L-shaped in vertical cross-section. The track-rail section 17 is preferably provided with a longitudinally extending slot 22, to receive the horizontal portion or web of the track-support 21, as 15 shown.

The numeral 23 designates preferably longitudinally foldable doors, arranged upon opposite sides of the post 11 to normally separate the front and rear rooms. 20 For the purpose of illustration, I have shown each of these doors as being formed of vertical panels 24, hinged at 25. To the upper ends of the panels 24 are pivoted, as shown at 26, inverted approximately L- 25 shaped hangers 27, slidably engaging with the track-rails.

In the operation of the apparatus, when it is desired to throw the front and rear rooms into complete or free communication 30 with each other, the door or doors upon each side of the post 11 are folded longitudinally, as illustrated in Fig. 2. This having been done, the transfer track-rail section 17 is swung in the proper direction, 35 whereby its free end is brought into registration with the corresponding end of the track-rail 14 or 15. The door is then moved longitudinally of the track-rail 14 or 15 onto the transfer track-rail section 17, sub- 40 sequent to which said transfer track-rail section is swung away from the track-rail to bring its free end into registration with the corresponding end of the track-rail 16. The door is then moved longitudinally of the 45 transfer track-rail section onto the track-rail 16, and longitudinally of the same to the rear end of the room, to occupy a position whereby it will be out of the way and will not obstruct the view. It is obvious 50 that the transfer track-rail section 17 is adapted to be used in transferring doors from both track-rails 14 and 15, to track- rail 16.

It is to be understood that the form of 55 my invention herewith shown and described is to be taken as a preferred example of the same, and that various changes in the shape, size and arrangement of parts may be resorted to without departing from the 60 spirit of the invention or the scope of the subjoined claims.

Having described my invention, I claim:—
1. In apparatus of the character described,

a plurality of spaced track-rails arranged in end to end relation, a separate track-rail ar- 65 ranged near and spaced from the first named track-rails and disposed approximately at right angles thereto, a pivoted transfer track-rail section arranged to have its free end brought into registration with the corre- 70 sponding end of each of the track-rails, and doors suspended from and longitudinally movable upon the track-rails.

2. In apparatus of the character described, a suitably supported track-rail, a second 75 suitably supported track-rail arranged near and spaced from the same, a suitably supported pivoted transfer track-rail section arranged between the ends of the track-rails and movable whereby its free end may be 80 brought into registration with the corresponding end of each of the track-rails, and a longitudinally movable door suspended from one track-rail.

3. In apparatus of the character described, 85 a track-rail adapted to be suspended from the ceiling of a room, a second track-rail adapted to be suspended from the ceiling and arranged at an angle to the first named track-rail, a transfer track-rail section piv- 90 otally supported between the inner ends of the track-rails to be swung in a substan- tially horizontal plane to bring its free end into registration with the corresponding end 95 of each track-rail, a foldable door, and hang- ers pivoted to the foldable door and nor- mally slidably engaging with one track- rail.

4. In apparatus of the character described, 100 a track-rail adapted to be arranged near the ceiling of a room, a second track-rail adapted to be arranged near the ceiling of a room and at an angle to the first named track-rail, a horizontally swinging transfer track-rail section arranged between the ad- 105 jacent ends of the track-rails and adapted to have its free end movable into registration with the adjacent end of each track- rail, pivot means for supporting the inner end of the transfer track-rail section, a track- 110 support having slidable engagement with the free end of the transfer track-rail section to support the same, a door, and hang- ers connected therewith and normally en- 115 gaging one track-rail to be moved longi- tudinally thereof.

5. In apparatus of the character described, 120 transverse track-rails having their inner ends spaced and adapted to be arranged near the ceiling of a room, a longitudinal track- rail adapted to be arranged near the ceiling of a room, a post arranged between the inner ends of the transverse track-rails, a transfer track-rail section pivoted to the post to swing in a horizontal plane whereby its free 125 end may be brought into registration with

the adjacent end of each of the track-rails, a curved track-support arranged adjacent the inner ends of the track-rails and having 5
slidable engagement with the free end of the transfer track-rail section, doors normally arranged beneath and adjacent the transverse track-rails upon opposite sides of the post, and hangers connected with the

doors and engaging the transverse track-rails.

10

In testimony whereof I affix my signature in presence of two witnesses.

JOHN E. MATTHEWS.
